Primary Examiner — Paula Greene(74) *Attorney, Agent, or Firm* — Birch, Stewart, Kolasch & Birch, LLP(57) **CLAIM**

The ornamental design for wireless headset, as shown and described.

DESCRIPTION

FIG. 1 is a perspective view of a wireless headset showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a reference view thereof showing that the head part of the earphone can be detached;

FIG. 9 is a reference view thereof showing that the earphone part can be detached; and,

FIG. 10 is a reference view thereof showing an example of the usage of the subject design in which the earphone part has been detached.

The broken lines depict portions of the wireless headset that form no part of the claimed design.

1 Claim, 9 Drawing Sheets---
